Attorney.

UNITED STATES PATENT OFFICE.

HOWARD A. GATES, OF CINCINNATI, OHIO.

STEAM-GENERATOR.

1,288,557.

Specification of Letters Patent. Patented Dec. 24, 1918.

Application filed October 3, 1918. Serial No. 256,639.

To all whom it may concern:

Be it known that I, HOWARD A. GATES, a citizen of the United States of America, and a resident of Cincinnati, in the county of 5 Hamilton and State of Ohio, have invented a new and useful Improvement in Steam-Generators, of which the following is a specification.

My invention relates to steam generators 10 and particularly to steam generators adapted for use in automobiles and tractors.

An object of my invention is a generator which by a simple means quickly vaporizes and burns as fuel hydro-carbon oils.

15 Another object of my invention is a generator which may be put into operation readily, as by the throwing of a switch.

A further object of my invention is a generator in which the pressure of the steam 20 may control the admission of the fuel to the combustion chamber.

These objects are attained by the means described in the following specification and illustrated in the accompanying drawings 25 in which:—

Figure 1, is a view partly in longitudinal section and partly in side elevation of a steam generator embodying my invention.

Fig. 2, is an enlarged detail partly in section and partly in side elevation of a fuel valve and regulator therefor.

Fig. 3, is an enlarged sectional view of the oil controlled switch forming a detail of my invention.

Fig. 4, is a sectional view of the pump upon line 4—4 Fig. 1.

Fig. 1^a, is a detail sectional view of the one-way clutch which connects the crank shaft with the gear wheel that is in mesh 40 with the shaft of the electric motor.

In my generator fuel siphons into a chamber A, and is sprayed by an air blower B run by an internal combustion engine C, whose exhaust gases are directed by exhaust pipe D 45 into initial combustion chamber A to ignite the sprayed fuel, which is thence conveyed by the blast of the blower into complete combustion chamber E of the boiler e, by means of the Venturi tube A¹.

50 Engine C may be started by an electric motor F, the circuit to which is intercepted by two switches, one a switch G, which is adapted to be opened and closed by variations of the steam pressure in boiler e, and the 55 other a switch H which is opened to stop

the motor when a certain amount of oil has been pumped into cylinder h by engine C.

I will now describe the parts of my generator in detail.

Engine C is of the internal combustion 60 class. The fuel is led thereto from a reservoir not shown, by pipe c through a fuel controlling feed valve c¹, whose valve stem c² is in contact with a lever c³, which is connected by a link with the lever g, of switch 65 G, which in turn is connected to the stem g¹ of the spring pressed piston g² in housing g³ whose inner end is in communication with the interior of the boiler e.

When the valve c² is seated it closes the 70 auxiliary ports c⁴, c⁵, and cuts off the supply of oil to the chambers c⁸, c⁹, of the feed valve c¹, (see Fig. 2).

A feed pipe d leads to the piston cylinders d¹ of the engine, from the chamber c⁹. 75 A feed pipe a leads from chamber c⁸ to the housing a¹ of a needle valve which extends into chamber A, which is connected by a pipe b with the housing b¹ of the blower, which is mounted upon crank shaft c¹⁰ of the 80 engine. Air is admitted to the blower by the port b².

Crank shaft c¹⁰ has upon it the usual fly wheel c¹¹. Large gear wheel c¹² is mounted upon crank shaft c¹⁰ by a one-way clutch 85 c¹³ of ordinary construction. In mesh with gear wheel c¹² is a pinion f which is secured to the shaft of motor F. Motor F is actuated by a storage battery K, from which one wire k leads directly to the motor, the other 90 wire k¹ leads to the switch k², thence a wire k³ leads to the switch G. Thence a wire k⁴ leads to a switch H. Thence a wire k⁵ leads to the motor.

Housing h of the oil switch is mounted 95 upon the crank case of engine C. Housing h has an admission pipe h² and exit port h³, which communicate with the oil pump M which is adapted to circulate a supply of oil from the crank case through housing h. 100 Pump M is operated by gears m which are actuated by the crank shaft c¹⁰. Switch H is actuated by the stem h¹ of piston valve h⁴ between which and the top of the housing is mounted a coil spring h⁵. 105

In operation; when the engine C is at rest, there will be no oil in the housing h, and spring h⁵ will have carried piston h⁴ to the bottom of the housing and the switch H will be closed. When the steam in the boiler e 110

- is below the pressure at which it is desired to run the engine, as for instance, 600 pounds, the spring in the housing g^3 will have carried the piston g^2 inwardly and will have closed switch g and will have raised valve c^2 to admit fuel to chambers c^8 , c^9 . Needle valve a^2 and hand valve d^2 being opened fuel will be admitted to the housing a^1 and to cylinders d^1 of the engine C.
- 10 When switch k^2 is closed the circuit through the motor F will be closed through wire k^3 switch G wire k^4 to switch H, wire k^5 and wire k to the battery K. Crank shaft c^{10} will then be rotated through pinion f of gear wheel c^{12} and one-way clutch c^{13} . The crank shaft c^{10} will then actuate blower B and force air through pipe b past the needle valve housing a^1 , and by suction draw the fuel therefrom and spray it across the mouth 75 of the exhaust pipe d of the engine. The rotation of the crank shaft will have reciprocated the pistons in the cylinders d^1 , and compressed the fuel therein, to be ignited in the usual way. The exhaust gases 80 20 issuing from the pipe d being inflamed will ignite the fuel which is being sprayed from the needle valve by the air pump. The ignited gases pass through the flame tube A¹ into chamber E to heat the water in the 85 boiler e. Pump M starts to pump oil from the bottom of the crank case into the housing h through admission port h^2 , as soon as the crank shaft c^{10} starts to rotate. This 90 raises piston h^4 and its stem h^1 and breaks 95 the circuit at the switch H. This will cause the motor F to stop. The pump M will maintain the circulation of oil into housing H through port h^2 , and out through port h^3 as long as the engine is in operation.

When the pressure exceeds the pre-determined limit it will force piston g^2 outward, move lever g and cause lever c^3 to close valve c^2 and cut off the supply of fuel both to the 45 engine and to the chamber A. The movement of the piston g^2 also opens the switch G. The stoppage of the engine likewise stops the pump M and spring h^5 will then seat the piston h^4 and close the switch H. If the 50 switch k^2 be left closed, as soon as the pressure in the boiler falls below the pre-determined limit piston g^2 will be moved inward by its spring to close switch G, then the circuit through the motor will be closed. The 55 motor will rotate and cause the operation just described to be repeated. If it be desired to prevent the automatic starting of the engine the switch k^2 is opened.

Having thus described my invention, what 60 I claim is:—

1. In a liquid fuel burner the combination of a combustion chamber, an internal combustion engine, a pipe from the engine adapted to discharge exhaust gases from the 65 engine into the combustion chamber, and

means for discharging a mixture of the liquid fuel and air into the combustion chamber to contact with the inflamed gases.

2. In a liquid fuel burner the combination of a combustion chamber, an internal combustion engine, an exhaust pipe from the engine discharging into the combustion chamber, a fuel feeder leading into the combustion chamber, an air blower adapted to spray the fuel from the feeder across the mouth of the exhaust pipe, and a connecting means between the blower and the engine.

3. In a steam generator for a boiler the combination of a liquid fuel burner comprising a combustion chamber, an internal combustion engine, an exhaust pipe from the engine discharging into the combustion chamber, a fuel feed valve adapted to control the flow of the fuel to the engine and to the combustion chamber, means for discharging a mixture of the fuel and air into the combustion chamber to contact with the inflamed products from the exhaust pipe, and an actuator for the fuel feed valve adapted to be moved to open or close the valve by variations of pressure in the boiler.

4. In a liquid fuel burner the combination of a combustion chamber, an internal combustion engine, an exhaust pipe for the engine discharging into the combustion chamber, a means actuated by the engine for discharging a mixture of the liquid fuel and air into the combustion chamber and to contact with the inflamed products from the exhaust pipe, an electric starter for the engine, an electric circuit for the starter, and a switch interposed in the circuit and adapted to be opened by the running of the engine, and to be closed when the engine stops.

5. In a steam generator for a boiler the combination of a liquid fuel burner, comprising a combustion chamber, an internal combustion engine, an exhaust pipe for the engine discharging into the combustion chamber, a fuel feed line, a valve in the fuel feed line and adapted to control the flow of the fuel to the engine and to the combustion chamber, an actuator for the valve adapted to be moved by variations of pressure in the boiler to open and close the valve, an electric motor adapted to start the engine, an electric circuit for the motor, a switch in the circuit and means connecting the switch and the valve actuator whereby said actuator opens the switch when the pressure rises above, and closes it when the pressure falls below a certain limit.

6. In a steam generator for a boiler the combination of a liquid fuel burner, comprising a combustion chamber, an internal combustion engine, an exhaust pipe for the engine discharging into the combustion chamber, a fuel feed line, pipes leading into the engine and the combustion chamber, a valve connecting the pipes to the fuel feed

- line and adapted to control the flow of the fuel to the engine and to the combustion chamber, a sprayer adapted to be actuated by the engine to spray the fuel into the combustion chamber, an actuator for the valve adapted to be moved by variations of pressure in the boiler to open and close the valve, an electric motor adapted to start the engine, an electric circuit for the motor, a switch in 5 the circuit, means connecting the switch and the valve actuator, whereby the said actuator opens the switch when the pressure rises above, and closes it when the pressure falls below a certain limit, a second switch inter- 10 posing in the circuit and means adapted to open the second switch when the engine starts to run and to close it when the engine stops. 15
7. In a steam generator for a boiler the combination of an internal combustion engine, a combustion chamber, an exhaust pipe from the engine adapted to discharge heated 20
- products of combustion into the combustion chamber, a fuel feed pipe, pipes leading into the engine and the combustion chamber, a 25 valve connecting the pipes to the fuel feed pipe adapted to control the flow of fuel to the engine and the combustion chamber, an actuator for the valve susceptible to the variations of pressure in the boiler, an air blower 30 mounted upon the crank shaft of the engine and adapted to spray the fuel from the feed pipe into the combustion chamber, an electric motor, a one-way clutch connecting the motor and the crank shaft of the engine, an 35 electric circuit in which the motor is interposed, a switch in the circuit adapted to be held open by a flow of fluid, and a pump for the fluid for the switch and adapted to be actuated by the engine. 40

In testimony whereof, I have hereunto subscribed my name this 30th day of September, 1918.

HOWARD A. GATES.
